FOREIGN PATENT DOCUMENTS

EP 1318953 6/2003

Primary Examiner — Deanna L Pratt*Assistant Examiner* — Katie Mroczka(74) *Attorney, Agent, or Firm* — The Reilly Intellectual Property Law Firm, P.C.(57) **CLAIM**

The ornamental design for an edible frozen treat catcher, as shown and described.

DESCRIPTION

FIG. 1 is a front perspective view of an edible frozen treat catcher;

FIG. 2 is a top view of the embodiment shown in FIG. 1;

FIG. 3 is a side view of FIG. 1; and,

FIG. 4 is an opposite side view of FIG. 1; and,

FIG. 5 is a bottom view of FIG. 1.

The broken line showing of the cone in FIG. 1 illustrates the environment of the claimed design and forms no part thereof.
